CHARLES J. BURKHARDT, OF HAZLETON, PENNSYLVANIA.

PUMP SYSTEM.

Application filed July 14, 1923. Serial No. 651,571.

To all whom it may concern:

Be it known that I, CHARLES J. BURKHARDT, a citizen of the United States of America, residing at Hazleton, in the county 5 of Luzerne and State of Pennsylvania, have invented certain new and useful Improvements in Pump Systems, of which the following is a specification.

My invention relates to pump systems and 10 particularly to pump systems in which the main pump has an associated priming pump, the present invention being applicable to pump systems in which both the priming pump and the main pump are automatically 15 controlled, substantially in the fashion indicated in the copending application of Otto Haentjens, filed July 14, 1923, Ser. No. 651,583. The object of my invention is to provide a device which will automatically 20 prevent repeated priming operations, where the priming operation is not followed by the proper functioning of the main pump.

In the accompanying drawing a system in 25 which my invention is embodied is diagrammatically illustrated.

In pumping systems of the type to which the present invention relates, the main pump is commonly of the centrifugal type, into 30 which the water is drawn from a sump by the priming pump before the centrifugal is set in motion. The priming pump motor is automatically started by a sump switch when the water in the sump reaches a predetermined level. After the priming operation 35 has been completed the circuit of the priming pump motor is automatically interrupted by a switch simultaneously with or shortly after the closing of the circuit of the centrifugal pump motor. If, however, upon the operation of the centrifugal 40 conditions are such that there is considerable air leakage to the centrifugal, the priming charge is lost and the centrifugal fails to function. The centrifugal motor circuit is 45 interrupted automatically through appropriate devices, and the priming pump circuit again closed. The priming operation is again repeated and the centrifugal again started in motion. If the leakage is again 50 sufficient to prevent the proper operation of the centrifugal, its motor again halts and the priming motor is again started and the cycle is repeated again and again until the attendant observes the condition and remedies the difficulty.

It is fair to assume that if a priming operation is thrice repeated without properly starting the centrifugal, some serious leakage difficulty is present which should be remedied. The present invention provides 60 an automatic control device which prevents the repetition of the priming operation more than a predetermined number of times.

Referring to the accompanying drawing, I have indicated at 1 the control circuit of 65 the priming pump, and at 2 the control circuit for the centrifugal pump motor. Arranged in the circuit 1 is a sump switch 3 which closes when the water in the sump reaches a predetermined level. The 70 closing of this circuit energizes the solenoid 4 which closes the circuit of the priming pump motor. It also energizes the solenoid 5 which controls the valve in the centrifugal pump casing which opens to the priming line between the pumps. Also arranged in the line 1 is a contactor 6 which is normally closed, but is automatically opened 75 simultaneously with or shortly after the closing of a float switch 7 which completes 80 the circuit through the solenoid 8 controlling the switch in the circuit of the centrifugal pump motor. The switch 7 is associated with a float chamber arranged in the priming line between the centrifugal and the 85 priming pumps and is float operated by the water which rises therein under the action of the priming pump, as disclosed in the copending application of Otto Haentjens above mentioned. Shunting the switch 7 90 which automatically opens when the water falls in the float chamber, is a circuit 9 in which are arranged switches 10 and 11 associated with vacuum and pressure regulators governing the centrifugal pump. The 95 vacuum regulator switch 10 is normally closed. The pressure regulator switch 11 is normally open and closes only when the centrifugal comes to speed and is delivering at the proper pressure.

The foregoing explanation of the general system will make clear the application of the present invention thereto. Arranged in the priming pump control circuit 1 is a solenoid 12, the armature 13 of which is connected by a link 14 to the lever 15 freely pivoted on spindle 16 carrying a pawl 17 which engages a pivoted ratchet member 18—here indicated in the form of a disc fast on the spindle 16. Keyed to the spindle 16 100

105

110

is a switch arm 19 adapted to travel over a series 20 of connected contacts *a*, *b*, *c* and *d* in line 1, and to move to "Off" position at *e*.

Associated with the ratchet disc 18 is a 5 detent 21 pivoted at 22 and connected by link 23 with the armature 24 of the solenoid 25 in a circuit 26 having a contact 27 in the path of the switch 11 and adapted for momentary engagement by the latter as it 10 moves to position to close the shunt 9. A stop lug 28 on the detent 21 engages the pawl 17 for actuation in the manner about to be described.

The operation of this device is as follows. 15 When the sump switch 3 closes the priming pump motor control circuit 1, the solenoid 12 is energized and its armature 13 rises, thus lifting the lever 15. The pawl 17, carried by the lever, rotates the ratchet disc 20 18 and causes the switch arm 19 to move from contact *a* to contact *b*. When the priming operation has been completed, and the centrifugal motor control circuit 2 25 closed at the float switch 7, the contactor 6 in the priming pump motor control circuit is automatically opened, thus de-energizing the solenoid 12 and permitting the lever 15 to drop by gravity. The ratchet disc 18, however, is maintained in position by the 30 detent 21, which engages the same. Should the centrifugal fail to come to speed, the pressure regulator switch 11 fails to close, and as soon as the float switch 7 opens by the fall of the water in the float chamber, the centrifugal pump control circuit 2 is opened and the contactor 6 of circuit 1 again closes. The cycle of operations is 35 repeated and the switch lever 19 moves from contact *b* to contact *c* on this second closure of the priming pump control circuit 1. Should the cycle of operations be again repeated, the switch arm 19 moves from contact *c* to contact *d*.

Three priming operations have now occurred without setting the centrifugal in 45 operation. Upon the succeeding closure of the priming motor control circuit 1, the switch lever 19 moves from the contact *d* to "Off" position at *e*, and the circuit is 50 automatically opened at this point before the priming pump has an opportunity to function. It cannot be again started until the circuit 1 is closed by the return of the ratchet disc 18 so that contact may be established by the switch arm 19 with one or 55 the other of the contacts *a*, *b*, *c* or *d* of the series 26. The release of the ratchet disc 18 may be accomplished either by hand 60 or automatically by the energization of the solenoid 25. The automatic energization of the solenoid 25 occurs when the pressure regulator switch 11 closes circuit 2. In the latter case the armature 24 rises and lifts the detent 21, thus holding the pawl 17 65 out of engagement with the ratchet disc

18, whereupon the latter returns to normal position through the action of a return spring or counterweight such as 29.

It is obvious that when, after the priming operation is performed, the centrifugal 70 starts and properly functions, the return of the ratchet disc 18 to normal position occurs automatically as soon as the pressure regulator switch 11 is closed by the delivery pressure of the centrifugal pump. 75

Obviously the contact series 20 could be arranged with equal effectiveness in the circuit 2 of the main pump motor. Again, it is not essential that both pumps be driven by electric motors. Nor is the conception 80 limited to electrically driven motors—it being readily applicable to steam, air or otherwise driven pumps.

The construction illustrated is obviously but a typical embodiment of the invention, 85 which may be modified in many ways without departing from what I claim.

I claim—

1. In a pump system, a main pump, a priming pump therefor, means automatically starting the main pump when primed, means automatically stopping the priming pump after it has performed its function, means automatically restarting the priming pump on failure of the main pump to function after priming, and means limiting the repetition of the cycle. 95

2. In a priming pump system, a main pump, a priming pump therefor, an electric motor for driving one of said pumps, means automatically starting the main pump when primed, means automatically stopping the priming pump after it has performed its function, means automatically restarting the priming pump on failure of the main pump to function after priming, and means 100 interrupting the circuit of said pump motor after predetermined repetitions of the cycle. 105

3. In a priming pump system, a main pump, a priming pump therefor, an electric motor for driving one of said pumps, means automatically starting the main pump when primed, means automatically stopping the priming pump after it has performed its function, means automatically restarting the priming pump on failure of the main pump to function after priming, and means interrupting the circuit of said pump motor after predetermined repetitions of the 110 cycle, together with means for automatically restoring the interrupter device to normal condition on functioning of the main pump. 115

4. In a priming pump system, a main pump, a priming pump therefor, an electric motor for driving one of said pumps, means automatically starting the main pump when primed, means automatically stopping the priming pump after it has performed its 120 125 function.

function, means automatically restarting the priming pump on failure of the main pump to function after priming, and means interrupting the circuit of said pump motor after predetermined repetitions of the cycle, together with means for automatically restoring the interrupter device to normal condition on functioning of the main pump within the permissible repetitions of the cycle. ¹⁰

In testimony whereof I have signed my name to this specification.

CHARLES J. BURKHARDT.
